US0D1028157S

(12) **United States Design Patent** (10) **Patent No.:** **US D1,028,157 S**
(45) **Date of Patent:** **** May 21, 2024**

(54) **SUPPRESSOR ENDCAP**

(71) Applicant: **Smith & Wesson Inc.**, Springfield, MA (US)

(72) Inventor: **Joseph DeJessa**, West Brookfield, MA (US)

(73) Assignee: **Smith & Wesson Inc.**, Springfield, MA (US)

(**) Term: **15 Years**

(21) Appl. No.: **29/827,589**

(22) Filed: **Feb. 21, 2022**

(51) **LOC (14) Cl.** **22-01**

(52) **U.S. Cl.**

USPC **D22/108**

(58) **Field of Classification Search**

(57) **CLAIM**

The ornamental design for an suppressor endcap, as shown and described.

DESCRIPTION

FIG. 1 is a perspective view of a suppressor endcap attached to an unclaimed suppressor shown in broken lines; FIG. 2 is a perspective view of the suppressor endcap; FIG. 3 is a left side view of the suppressor endcap, the right side view, top view, and bottom view in their respective orientations being identical thereto; and, FIG. 4 is a front view of the suppressor endcap, the back view forming no part of the claimed design. The broken lines in the drawings disclose unclaimed portions of the suppressor endcap only and form no part of the claimed design.
